LLP; M. Kala Sarvaiya; Steven C. Sereboff(57) **CLAIM**

The ornamental design for a rear light for a vehicle, as shown and described.

DESCRIPTION

A portion of the disclosure of this patent document contains material to which a claim for copyright is made. The copyright owner has no objection to the facsimile reproduction by anyone of the patent document or the patent disclosure, as it appears in the Patent and Trademark Office patent file or records, but reserves all other copyright rights whatsoever.

FIG. 1 is a front, top and right side perspective view of a rear light for a vehicle.

FIG. 2 is a rear, bottom and left side perspective view thereof;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof;

FIG. 8 is left side elevation view thereof.

FIG. 9 is a top elevation view thereof; and,

FIG. 10 is a bottom elevation view thereof.

The broken lines shown in the drawings are for illustrative purposes only and form no part of the claimed design.

1 Claim, 5 Drawing Sheets
